EXERCISER

William E. Sharp, Chicago, Ill.; Minnie E. Sharp
executrix of the estate of said Sharp, deceased

Application December 12, 1928, Serial No. 325,538

9 Claims. (Cl. 128—63)

This invention relates to vibrating or exercising machines and more particularly to one for vibrating an engaging member or belt adapted to surround a portion of the anatomy of an individual.

The principal object of my invention, generally considered, is to provide a rugged vibrating or exercising machine having a base which holds it firmly on the floor, a portion of said base being adapted to support the patient to be treated and the adjacent portion serving for the support and connection of the housing enclosing the power means and mechanism for effecting the vibration of the massaging belt, said belt being adjustable with respect to the machine even during the operation thereof, so that the degree of massage may be varied.

Another object of my invention is to provide a housing for a vibrating or exercising machine for holding an electric motor in position and supporting an upright shaft and intermediate mechanism for vibrating said shaft, vibrating arms being connected to the upper end of said shaft and formed with portions of reduced section for receiving the looped ends of a massaging belt in adjusted positions.

A further object of my invention is to provide an exercising machine comprising a base and housing resting thereon and enclosing the mechanism, that portion of the base extending beyond the housing being adapted to support the patient and being hinged for upward swinging out of the way when not in use, or being made in the form of removable rods which are received in sockets in the base of the machine and held in vertical position when said machine is not being used.

Other objects and advantages of the invention relating to the particular arrangement and construction of the various parts will become apparent as the description proceeds.

Referring to the drawings illustrating my invention, the scope whereof is defined by the appended claims.

Figure 1 is a vertical sectional view of one form of my exercising machine, portions of the enclosed mechanism being illustrated in elevation.

Figure 2 is an elevational view, at right angles to that shown in Figure 1, of the upper portion of the machine housing, the vibrating arms extending from the vertical vibratory shaft or rod of the machine and the massaging belt associated therewith.

Figure 3 is a fragmentary sectional view on the line 3—3 of Figure 2, looking in the direction of the arrows.

Figure 4 is a horizontal sectional view on the line 4—4 of Figure 1, looking in the direction of the arrows.

Figure 5 is a side elevational view of a modified form of machine, the lower portion only being illustrated.

Figure 6 is a plan of the embodiment of my invention illustrated in Figure 5, portions of the vibrating arms being broken away.

Figure 7 is a perspective of a cabinet or screen adapted to enclose the form of machine shown in Figures 5 and 6 when not in use.

Figure 8 is a fragmentary sectional view corresponding to Figure 1, but showing a further embodiment of my invention.

Figure 9 is a fragmentary view corresponding to Figure 2, but showing a modified form of vibrating or handle bar and associated massaging belt.

Figure 10 is a sectional view on the line 10—10 of Figure 9, looking in the direction of the arrows.

Referring to the drawings in detail, like parts being designated by like reference characters, and first considering the embodiment of my invention illustrated in Figures 1 to 4 inclusive, I have shown an exercising machine comprising a base 1 preferably formed as a casting with a horizontal upper web 2 upon which, or upon lugs or ribs 3 thereon, rests a housing 4 preferably formed as a casting and serving to enclose an electric motor or other power means 5 for imparting vibration or oscillation to an upright or vertical shaft or rod 6, the housing 4 preferably comprising an inner framing 7 which is desirably cast and connected to the housing proper by a plurality of screws or the like 8. Said housing and inner framing are desirably securely connected to the base 1 by a plurality of screws or bolts 9.

The base 1, which has an upper web 2, normally horizontal where it supports the housing 4, is preferably provided with a downward embossment 10 in said web forming a pocket beneath the motor 5 for receiving any oil or grease drippings from the mechanism and also providing the necessary clearance between the motor and base. The web 2 beyond the housing 4 preferably slopes, as indicated at 11, so that the patient 12 can stand on the sloping portion and lean backwardly against the massaging belt 13, and at the same time maintain the normal angularity between feet and legs. The web portion 11 is preferably formed with a depression 14 adapted to receive a mat 15 of rubber or fabric. For rigidifying the base, the outer edges of the webs 55

2 and 11 are downwardly flanged as indicated at 16 and intermediate ribs or gussets 17 are also desirably provided.

The frame 7 not only serves to support the 5 motor 5, as by means of bolts 18, but also forms seats for the bearings 19 and 20, thereby holding them securely in place and maintaining the desired relation therebetween. The motor 5 is desirably supported with its shaft 21 extending vertically or upright and keyed to a larger rod or shaft 22 rotating in the bearing 19, which is preferably a ball bearing, as illustrated. Above the bearing 19 is a preferably smaller bearing 23, eccentric to the bearing 19, and a counter-balance weight 24 extending opposite from the eccentricity of the bearing 23 to balance the centrifugal force of the reciprocating or oscillating link 25, one end of which is connected to the shaft 22 at the bearing 23, and the other end 10 of which is pivotally connected to a vibrating arm or crank 26 mounted on the lower end of the vibrating, oscillating or pivotally mounted shaft 6 preferably below the bearing 20, as by means of a pin 21. The link 25 may be held on the bearing 23 in any desired manner as by means of a washer 28 and bolt 29. The crank or rod 26 is non-rotatably connected on the vibrating shaft 6 in any desired manner as by means of a set screw 30. The upper end of the shaft 6 is rotatably mounted in a bearing 31, and non-rotatably or rigidly connected to said upper end 15 is a pair of handle bars or vibrating arms 32 extending outwardly in opposite directions from a hub or operating head 33 which may be keyed or otherwise non-rotatably or rigidly connected to the shaft 6 and held thereon by a nut and washer 34 and 35.

In order to adjust the amplitude or intensity of vibration imparted from the handle bar 32 to the massaging belt 13, said handle bar is formed of varying cross section, as indicated, or with a series of portions 36 of reduced section, and each end of the belt 13 is desirably provided with a loop 37 fitting over the handle bar or rods 32 and adapted to be moved to the desired location on said bar and held in place on the portions 36 of reduced section. The loops 37 are formed of such size that they may be readily moved on the handle bar 32 to the desired location, even when the bar is vibrating, but are tight enough on the bar so that they will not slip of their own accord. It will therefore be apparent that the patient 12 may stand on the platform or base 1 and place the belt around the body, start the machine by moving a switch or pushing a button 38 and receive vibration and massage from the corresponding vibration of the belt 13 imparted from the vibrating handle bars 32, and such massage may be varied at will while the machine is operating by moving the loops 37 together or apart to the desired positions on the handle bars.

Referring now to the embodiment of my invention illustrated in Figures 5, 6 and 7, an embodiment is illustrated in which the base 1^a of the machine is much smaller and approximately the size of the lower portion of the housing 4^a, so that it takes up much less floor space than the base of the previous embodiment. In order to increase the stability of the machine when being used, a pair of rods or bars 39 are employed fitting in sockets 40 in the base 1^a so that they normally extend approximately horizontally for increasing the effective outline of the base. In order to avoid marring the floor on which the machine stands, the ends of the bars 39 are de-

sirably provided with balls or cushions 41 of rubber or the like normally engaging the floor. When the machine is not in use, the bars 39 may be pulled out of the sockets 40, in which they may be either fit snugly or be threaded thereinto or be held in any desired manner, and inserted in similar sockets 42 in the base 1^a opening upwardly, so that said bars 39 are held in upright or vertical positions, thereby effecting a saving in floor area and having them out of the way 10 when the machine is not in use. If it is desired to further stabilize the machine or hold it in one place on the floor, bolts 43 may extend through said base into the floor and/or hooks 44 may be connected to the wall 45 as by means of screws 15 or bolts 46 and engage lugs 47 on the sides of the housing 4^a. In order to conceal the exercising machine when not in use, a decorative cabinet or cover 48, occupying a relatively small floor area, with two side walls, a front wall and a top 20 may be employed to cover the machine after the bars 39 have been placed in upright inoperative positions. Except as specifically described and illustrated in Figures 5, 6 and 7, the exerciser may correspond with that of Figures 1 to 4 inclusive. 25

Referring now to the embodiment of my invention illustrated in Figures 8, 9 and 10, a machine is shown with a base 1^b comprising a housing supporting portion 48 and a patient supporting portion 49. The housing supporting portion 30 48 may support a housing 4^b similar to or identical with the housing 4 of the first embodiment, and the motor 5^b and enclosed mechanism may correspond with that of the first embodiment. In order to get the patient supporting portion 49 35 out of the way when not in use, the same is hinged to the housing supporting portion 48, as by means of hinge bolts or pins 50 through preferably integral lugs 51 on the housing supporting portion and 52 on the patient supporting portion. In order to avoid starting the machine and having it pulled over on the patient while being used due to the hinging between parts 48 and 49, a latch 53 is provided which normally locks the parts together in line, as illustrated, but which 45 may be released to permit upward swinging of the part 49 by pulling the bell crank lever 54 connected to the release rod 55 which is spring actuated to normally urge the wedge 56 between the upper web of the part 49 and the adjacent 50 end of the latch 53 to urge the other heavier end 57 of said latch into engagement with a flange or shoulder 58 on the housing supporting portion 48 for locking the parts together. When the bell crank lever 54 is pulled out, the latching end 55 57 of the latch 53 is permitted to drop by gravity and release the patient supporting platform 49 and permit it to be rotated into inoperative upright position.

In order to break the circuit to the motor 5 and prevent operation thereof when the platform 49 is unlocked or raised, the latching end 57 engages a switch 59 and causes contact to be made between contact piece 60 on the switch and 61 on engaging contact arm so that the circuit is closed 65 through lead-in wires 62 and 63 which are in series with the circuit to the motor 5 permitting the operation thereof. When the bell crank lever 54 is pulled outwardly, the latch portion 57 is permitted to drop and allows the engaged heavier 70 end of the switch 59 to drop and break contact between the blocks 60 and 61 opening the circuit through the motor 5 and preventing operation thereof. In order to always maintain the latch in locked position until manually operated. to 75

release if, the wedge is urged into engagement with said latch by resilient means such as a helical spring 64 in compression between said wedge and a guiding lug 65 on the platform 49.

5 The handle bar or vibrating rods 32^b of the present embodiment may correspond with the first embodiment or may be of substantially uniform diameter with a series of notches 66 above and below for engagement with eyelets 67 in
10 the ends of the massaging belt 13^b. Said eyelets are preferably so formed that the belt freely slips over the ends of the handle bar 32^b when in the position shown in Figure 10, and upon pulling on the belt, the reduced portions 68 of
15 the eyelets engage in the notches 66 and hold the belt in adjusted position on the handle bars so that the degree of massage may be freely adjusted even while the bars are vibrating, although not quite as easily as with the arrangement of
20 the first embodiment.

From the foregoing description taken in connection with the accompanying drawings, it will be seen that I have provided an exercising or vibrating machine of rugged construction in which 25 the rotating or vibrating parts are firmly mounted in bearings of ample size, all of said bearings being enclosed in a dust proof housing and supported on a base adapted to catch all grease or oil and prevent soiling of the floor or carpet on
30 which the machine may rest. In modified forms, I have shown how the floor space for the machine may be economized when said machine is not being used, either by removing and reinserting stabilizing rods or by swinging the patient 35 supporting base or platform to inoperative position. One particularly important feature of my invention is the provision for readily adjusting the amount of massage or vibration transmitted from the machine even while said machine is in motion. In the first embodiment illustrated, it 40 will be noted that by virtue of the sloping platform or patient supporting portion of the base, I have not only economized in weight of metal used for the base, but have also reduced the 45 height of the patient supporting portion at the outer end above the supporting floor, thereby reducing the possibility of tripping over the platform and making it possible for the patient to lean back against the encircling belt while still
50 maintaining the normal angular relation between the feet and legs, thereby enabling a more restful posture to be maintained.

Having now described my invention, I claim:

1. In an exercising machine, a base, a casing 55 extending upwardly from said base and enclosing an upright rod mounted for oscillation about its axis and power means for vibrating said rod, arms connected to, and extending in opposite directions from the upper end of said rod for being vibrated thereby, and a belt adjustably associated with said arms for imparting massage to a person standing on said base, that portion of said base upon which the person stands sloping away from the housing for the purpose described.

65 2. In an exercising machine, a base adapted to support the machine at all times, a housing disposed thereon, an upright rod mounted for oscillation about its axis and enclosed in said housing, arms rigid with said rod and extending therefrom in opposite directions and power means for operating said rod for imparting vibration to said arms comprising a housing-supporting portion and a patient-supporting portion hinged together adjacent one edge of said housing, whereby when
70 the machine is not in use, the patient-supporting

portion may be folded upward from the floor to stand alongside of the housing.

3. In an exercising machine, a base serving to support the mechanism of the machine and a patient to be treated, a housing connected to one end of said base, power means in the lower portion of said housing, and an upright rod mounted for oscillation about its axis in the upper portion thereof adapted to be oscillated by said power means, that portion of the base upon which the patient stands being hinged to the remainder of the base and adapted to be rotated from horizontal operative position to vertical inoperative position to economize space when not in use, and means for locking said hinged portion of the base to the remainder thereof in horizontal position, the unlocking of said hinged portion from the remainder thereof serving to break the energy circuit to the power means in the housing and prevent operation of the machine. 20

4. In an exercising machine, a base, a housing resting on said base and enclosing the mechanism of the machine, and means for increasing the stability of the base when the machine is being used comprising rods extending horizontally from said base to normally engage the floor and increase the effective bearing area of the base, said rods, when the machine is not in use, being adapted for removal and insertion in vertical position in the base of the machine. 30

5. An exercising machine comprising a base, a casing mounted on said base, an upright shaft mounted in said casing mechanism enclosed in said casing for vibrating said shaft, arms extending outwardly from the upper end of said shaft and movable therewith for imparting vibration to an associated massaging belt, the base including a patient supporting portion sloping away from the casing so that the patient can lean backward slightly against the massaging belt while maintaining substantially normal relation between feet and legs. 35

6. An exercising machine comprising a base, a mechanism enclosing housing mounted on said base, said base having an upper web, said web beneath the mechanism in the housing being depressed to provide clearance and form a lubricant catching pocket. 45

7. An exercising machine comprising mechanism operating a massaging belt, a base for supporting said mechanism and a patient to be treated thereby, that portion of the base adapted to support the patient sloping to allow the patient to lean against the belt and still maintain normal relative foot angularity and formed with a depression, and a resilient mat mounted in said depression. 50

8. An exercising machine comprising an operating head, a supporting base, means supporting said head upon said base, operating mechanism for said head comprising a motor, means for transmitting motion from said motor to said head, a platform for the user movable from an extended operative position to a retracted inoperative position, and means associated with said platform for rendering the machine inoperative when said platform is disposed in retracted position. 60

9. An exercising machine comprising a base, power means mounted thereon, said base comprising a housing for said power means including a hollow upright, an operating head supported adjacent the top of said upright, means extending through said upright for transmitting motion 75

to said head, a pair of rigid arms extending in opposite directions from said head and formed with a plurality of longitudinally spaced annular rounded beads alternating with annular curved 5 depressions, and a massaging belt with looped ends one of which engages a depression in one

arm and the other a corresponding depression in the other arm, whereby the amplitude of vibration imparted to said belt may be varied by slipping the loops over said beads into other notches along said arms. 5

WILLIAM E. SHARP.
